DESIGN FOR A HAMMER TOY

Edward D. Geissler, Detroit, Mich.

Application October 19, 1945, Serial No. 123,032

Term of patent 3½ years

(Cl. D34—15)

To all whom it may concern:

Be it known that I, Edward D. Geissler, a citizen of the United States, residing at Detroit, in the county of Wayne and State of Michigan, have invented a new, original, and ornamental Design for a Hammer Toy, of which the following is a specification, reference being had to the accom-

panying drawing, forming a part thereof, in which the figure is a view in perspective of a hammer toy, showing my new design.

I claim:

The ornamental design for a hammer toy, substantially as shown.

EDWARD D. GEISSLER.
